E. W. Marshall

UNITED STATES PATENT OFFICE.

JOSEPH KENNEDY, OF NEW YORK, N. Y., ASSIGNOR TO JOHN EDWARD OGDEN, OF MOUNTAINVILLE, NEW YORK.

BOLT ANCHOR.

1,410,260.

Specification of Letters Patent. Patented Mar. 21, 1922.

Original application filed March 29, 1919, Serial No. 286,126. Divided and this application filed April 3, 1920. Serial No. 370,953.

To all whom it may concern:

Be it known that I, JOSEPH KENNEDY, a citizen of the United States of America, and a resident of New York City, county and State of New York, have invented certain new and useful Improvements in Bolt Anchors, of which the following is a specification, reference being had to the accompanying drawings, forming a part thereof.

10 My invention relates to improvements in bolt anchors which are designed to be used for bolt anchorages and to a new and useful method of manufacturing such shields. More specifically, it relates to expansion shields which are made of sheet metal and to a method of making such shields of sheet metal.

15 The object of this invention is to provide a simple and inexpensive device which may be effectively used to hold a bolt or screw in material such as brick, stone or cement with which the threaded device cannot obtain directly a secure hold.

Another object is to provide a simple and inexpensive method of making such expansion shields.

In order that my invention may be thoroughly understood I will now proceed to describe the same in the following specification, and will then point out the novel features thereof in appended claims.

This application is a division of application, Serial No. 286,126, filed by me March 29, 1919.

35 Referring to the drawings:

Figure 1 is a plan view of an undivided blank of sheet metal of general arcuate form which may be bent into a shield which embodies this invention.

40 Figure 2 is an end view showing the blank of Fig. 1, after it has received its first bending.

Figure 3 is a side elevation of an expansion shield made by folding together a blank 45 of the preceding figures.

Figure 4 is a top plan view of this shield.

Figure 5 is a bottom plan view of the same shield.

50 Figure 6 is an elevation of the shield shown in Fig. 3, taken at right angles to the view in the latter figure.

Figure 7 is an elevation of the same de-

vice showing the opposite side to that shown in Fig. 6.

Figure 8 is an end elevation of a shield of modified form of construction which also embodies this invention.

Figure 9 is a view similar to Fig. 8, which shows a shield of a still further modified form.

Like characters of reference designate corresponding parts in all the figures of the drawings.

60 designates a blank of sheet metal of general arcuate form although its upper 65 sides 61 are cut to flare outwardly slightly to the upper edge. Between these edges and the rest of the edges which flare outwardly in the other direction are indentations or notches 62, and in the center of the blank 70 is a perforation 63 in arcuate alinement with the indentations 62. 64 is a slot cut vertically in this blank but terminating at 65 short of the lower edge of the blank.

From one of the upper edges 61 is a triangular projection 66 opposite which in the other edge 61 is an indentation 67 of less angularity than that of the projection 66. The dotted lines 68—68 designate portions of this blank which are to be pinched together to form short outwardly projecting ribs 70 in the finished shield. The lines 69 designate portions of the blank which are to be stamped into corrugations which in the finished shield are designated by 71.

75 The first step towards forming a shield from such a blank after it has been corrugated is illustrated in Fig. 2 which shows portions of the blank bent into transverse curves 72 with an intermediate curved portion 73 connected with the parts 72 along lines at 74. The outer edges of the blank 80 are also bent to form curved portions 75—75 joined to the portions 72 along lines at 76.

85 The shield is then finished by folding the 95 blank thus formed around a central axis as shown in Figs. 3-7. The upper end of the shield thus formed will be substantially circular as shown at 77 in Fig. 4 with the short ribs 70 projecting outwardly therefrom. 100 This upper portion of the shield, however, will flare outwardly towards the upper end of the shield, and this form is provided for the purpose of closely fitting the outer end

- of the hole in which the shield is to be used and of facilitating the insertion of a bolt or screw. The parts 74 and 76, however, are so arranged that when the shield is completed they will converge towards the lower end of the shield to make the interior thereof similar in cross sectional form to an hour-glass, that is, these parts will converge to restrict the bore of the shield in one of its transverse dimensions. The outer portion of the shield will be cylindrical substantially throughout its length and of a diameter corresponding approximately with that of the hole in which the device is to be used. The part of the shield which is formed of the portion 73 will increase in cross sectional dimension towards the lower end of the shield and so will the opposite part of the shield which is formed of the parts 75—75. The slot 64 when used will divide the part of the shield formed by the portion 73 throughout the greater part of the length of the shield and the opposite part formed by the portions 75 will be divided throughout the length of the shield.
- When the blank is folded together to form the tubular shield the projection 66 will register with the indentation 67 as shown in Fig. 6, and will serve to hold the edges of the shield in alignment in such a manner as to maintain the corrugations 71 in helical alignment. These corrugations are provided for the purpose of forming the inner bore of the shield with internal screw threads with which the threads of a bolt or screw may engage. It may be seen that the shield thus formed has a central chamber which diminishes from a cylindrical form at the upper end (Fig. 4) to that of an hour-glass form (Fig. 5) at the lower end. When a bolt is inserted this part of the shield will be spread apart by the bolt. The transverse dimension of the restricted part of the bore of this device is, however, substantially the same as that of the internal periphery of the shield at its upper end, so that when the bolt is inserted the metal of the shield will substantially surround the threads of the bolt without interruption throughout the length of the shield. The completed shield has two longitudinal chambers formed within the parts made by the portion 73 and the portions 75—75. These chambers increase in size towards the lower end of the shield so that they provide an excess of metal which when the bolt is inserted, will be crowded between the bolt and the wall of the hole in which the shield is inserted to thus form a secure anchorage.
- It is not necessary that the constriction of the bore of the device be made in hour-glass form. For example, in Fig. 8 the inner end of a shield is shown with the inwardly projecting portions 78 and the abutting edges 79 symmetrically disposed.

Figure 9 shows the inner end of a shield similar in construction to that already described but with the inner end 80 of the bore elliptical in form instead of constricted into an hour-glass cross sectional form.

The structures thus described are tapered tubes having an excess of metal near the inner ends thereof. It is only necessary that this taper be formed at some time before the bolt is to be inserted, and this taper may be formed by driving the shield into a cylindrical hole prepared for it, which act will contract the inner end of the shield, if it has not been constructed previously with the tapered bore.

What I claim is:

1. An expansion shield blank of sheet metal with a part of the sides thereof near one end approximately parallel, the rest of the sides of said blank flaring therefrom, said blank being arranged to be folded transversely into a tube, the circumference of which approximates the distance between said parallel parts and the flaring portion arranged to be bent to provide excess metal in other parts of the tube, said blank being constructed with an angular indentation on one of said first-mentioned parts of its sides and having an angular cooperating projection on the opposite side, arranged to prevent the longitudinal displacement of these sides when brought together to form the tube.

2. An expansion shield blank of sheet metal, with a part of the sides thereof near one end approximately parallel, the rest of the sides of said blank flaring therefrom and having transverse corrugations therein, said blank being arranged to be folded transversely into a tube, the circumference of which approximates the distance between said parallel parts and the flaring portion arranged to be bent to provide excess metal in other parts of the tube and to cause said corrugations to lie in a helix, said blank being constructed with an angular indentation on one of said first-mentioned parts of its sides and having an angular cooperating projection on the opposite side, arranged to prevent the longitudinal displacement of these sides when brought together to form the tube and to maintain the corrugations in their helical position.

3. An expansion shield blank of sheet metal with a part of the sides thereof near one end flaring slightly toward said end, the rest of the sides of said blank flaring toward the other end, transverse corrugations in the blank between said latter parts of its sides, said blank being arranged to be folded transversely into a tube, the circumference of which approximates the distance between said first mentioned part of the sides of the blank, and the other flaring portion arranged to be bent to provide excess metal in

other parts of the tube, and to cause said corrugations to lie in a helix, said blank being constructed with an angular indentation on one of said first mentioned parts of its sides 5 and having an angular cooperating projection on the opposite side, arranged to prevent the longitudinal displacement of these sides when brought together to form the tube and to maintain the corrugations in their 10 helical position.

4. An expansion shield blank of sheet metal, with a part of the sides thereof near one end approximately parallel, the rest of the sides of said blank flaring therefrom and 15 having transverse corrugations therein, said blank being arranged to be folded transversely into a tube, the circumference of which approximates the distance between said parallel parts and the flaring portion ar- 20 ranged to be bent to provide excess metal in other parts of the tube and to cause said corrugations to lie in a helix, said blank being constructed with an angular indentation on one of said first-mentioned parts of its sides 25 and having an angular cooperating projection on the opposite side, arranged to prevent the longitudinal displacement of these sides when brought together to form the tube and to maintain the corrugations in 30 their helical position, the angularity of the indentation being less than that of the projection.

5. An expansion shield blank of sheet metal with a part of the sides thereof near 35 one end flaring slightly toward said end, the rest of the sides of said blank flaring toward the other end, transverse corrugations in the blank between said latter parts of its sides and intermediate the central part and the 40 edges of the blank, said blank being ar- ranged to be folded transversely into a tube with the outer portions of greatest diameter lying substantially in the same cylinder, with opposite parts increasingly depressed to 45 form a bore tapered in one of its transverse dimensions with the central part of the blank folded over one of said depressions and with the edges of the blank folded over the other of said depressions to provide an excess of 50 metal over the tapered part of the bore, increasing in amount as said depressions increase.

6. An expansion shield blank of sheet metal with a part of the sides thereof near 55 one end flaring slightly toward said end, with parts of the metal between them pinched together to form outwardly projecting ribs, the rest of the sides of said blank flaring to- 60 ward the other end, transverse corrugations in the blank between said latter part of its sides and intermediate the central part and the edges of the blank, said blank being ar- ranged to be folded transversely into a tube with the outer portions of greatest diameter

lying substantially in the same cylinder, 65 with opposite parts increasingly depressed to form a bore tapered in one of its trans- verse dimensions with the central part of the blank folded over one of said depres- sions and with the edges of the blank folded 70 over the other of said depressions to pro- vide an excess of metal over the tapered part of the bore, increasing in amount as said depressions increase.

7. An expansion shield blank of sheet 75 metal with a part of the sides thereof, near one end flaring slightly toward said end, with parts of the metal between them pinched together to form tapered outwardly project- 80 ing ribs, the rest of the sides of said blank flaring toward the other end, transverse cor- rugations in the blank between said latter parts of its sides and intermediate the central part and the edges of the blank, said blank being arranged to be folded trans- 85 versely into a tube with the outer portions of greatest diameter lying substantially in the same cylinder, with opposite parts in- creasingly depressed to form a bore varying 90 from a circular cross-section to one of hour- glass form, with the central part of the blank folded over one of said depressions and with the edges of the blank folded over the other of said depressions to provide an excess of metal over the tapered part of the 95 bore, increasing in amount as said depres- sions increase.

8. An expansion shield blank of sheet metal with a part of the sides thereof near one end flaring slightly toward said end, with 100 parts of the metal between them pinched together to form outwardly projecting ribs, the rest of the sides of said blank flaring to- 105 ward the other end, transverse corrugations in the blank between said latter part of its sides and intermediate the central part and the edges of the blank, said blank being ar- ranged to be folded transversely into a tube with the outer portions of greatest diameter 110 lying substantially in the same cylinder, with opposite parts increasingly depressed to form a bore tapered in one of its trans- 115 verse dimensions with the central part of the blank folded over one of said depressions and with the edges of the blank folded over the other of said depressions to provide an excess of metal over the tapered part of the 120 bore, increasing in amount as said depres- sions increase, and to cause said corruga- tions to lie in a helix in the bore of said tube, said blank being constructed with an angular indentation on one of said first men- 125 tioned parts of its sides and having an angular cooperating projection on the opposite side, arranged to prevent the longitudinal displacement of these sides when brought together to form the tube and to maintain the corrugations in their helical position.

9. An expansion shield blank of sheet metal with a part of the sides thereof near one end flaring slightly toward said end, with parts of the metal between them pinched together to form tapered outwardly projecting ribs, the rest of the sides of said blank flaring toward the other end, transverse corrugations in the blank between said latter parts of its sides and intermediate the central part and the edges of the blank, said blank being arranged to be folded transversely into a tube with the outer portions of greatest diameter lying substantially in the same cylinder, with opposite parts 10 increasingly depressed to form a bore varying from a circular cross-section to one of hour-glass form, with the central part of the blank folded over one of said depressions and with the edges of the blank folded over the other of said depressions to provide an excess of metal over the tapered part of the bore, increasing in amount as said depressions increase, and to cause said corrugations to lie in a helix in the bore of said tube, said 20 blank being constructed with an angular indentation on one of said first mentioned parts of its sides and having an angular cooperating projection on the opposite side, arranged to prevent the longitudinal displacement of these sides when brought together to form the tube and to maintain the corrugations in their helical position, the angularity of the indentation being less than that of the projections.

25 10. An expansion shield blank of sheet metal with a part of the sides thereof near one end flaring slightly toward said end, with parts of the metal between them pinched together to form tapered outwardly projecting ribs, the rest of the sides of said blank flaring toward the other end, transverse corrugations in the blank between said latter parts of its sides and intermediate the central part and the edges of the blank, said blank being arranged to be folded transversely into a tube with the outer portions of greater diameter lying substantially in the same cylinder, with opposite parts 30 increasingly depressed to form a bore varying from a circular cross-section to one of hour-glass form, with the central part of the blank folded over one of said depressions and with the edges of the blank folded over the other of said depressions to provide an excess of metal over the tapered part of the bore, increasing in amount as said depressions increase, and to cause said corrugations to lie in a helix in the bore of said tube, said 35 blank being constructed with an angular indentation on one of said first mentioned parts of its sides and having an angular cooperating projection on the opposite side, arranged to prevent the longitudinal displacement of these sides when brought together to form the tube and to maintain the corrugations in their helical position, the angularity of the indentation being less than that of the projections.

40 11. An expansion shield of sheet metal folded transversely into a tube having edges of the metal extending from one end to the other thereof with the outer portions of said shield of greatest diameter lying substantially in the same cylinder, with opposite parts depressed to constrict the bore of the tube and to provide an excess of metal at the part of the tube of constricted bore.

45 12. An expansion shield of sheet metal, folded transversely into a tube having edges of the metal extending from one end to the other thereof with the outer portions of said shield of greatest diameter lying substantially in the same cylinder, with opposite parts depressed to constrict the bore of the tube and with parts adjacent said depressions bent to provide an excess of metal at the part of the tube of constricted bore.

50 13. An expansion shield of sheet metal having more metal at one end than at the other, folded transversely into a tube having edges of the metal extending from one end to the other thereof with the outer portions of said shield of greatest diameter lying substantially in the same cylinder, with opposite parts depressed to constrict the bore of the tube and with parts adjacent said depressions bent to provide an excess of metal at the part of the tube of constricted bore.

55 14. An expansion shield of sheet metal having more metal at one end than at the other, folded transversely into a tube having edges of the metal extending from one end to the other thereof with the outer portions of said shield of greatest diameter lying substantially in the same cylinder, with opposite parts depressed to constrict the bore of the tube in one of its transverse dimensions and with parts adjacent said depressions bent to provide an excess of metal at the part of the tube of constricted bore.

60 15. An expansion shield of sheet metal having more metal at one end than at the other, folded transversely into a tube having edges of the metal extending from one end to the other thereof with the outer portions of said shield of greatest diameter lying substantially in the same cylinder, with opposite parts increasingly depressed to form a bore tapered in one of its transverse dimensions, and with parts adjacent said depressions bent to provide an excess of metal increasing in amount as said depressions increase.

65 16. An expansion shield of sheet metal having more metal at one end than at the other, folded transversely into a tube with the outer portions of greatest diameter lying substantially in the same cylinder, with

- opposite parts increasingly depressed to form a bore tapered in one of its transverse dimensions with the central part of the metal folded over one of said depressions and with 5 the edges of the metal folded over the other of said depressions to provide an excess of metal over the tapered part of the bore, said excess of metal increasing in amount as said depressions increase in depth.
- 10 17. An expansion shield of sheet metal having more metal at one end than at the other, folded transversely into a tube with the outer portions of greatest diameter lying substantially in the same cylinder, with opposite parts increasingly depressed to form a bore tapered in one of its transverse dimensions with the central part of the blank folded over one of said depressions and with the edges of the metal folded over the other 15 of said depressions to provide an excess of metal over the tapered part of the bore, said excess of metal increasing in amount as said depressions increase in depth, said central part of the metal being cut away to form a 20 longitudinal slot.
18. An expansion shield of sheet metal having more metal at one end than at the other, folded transversely into a tube with the outer portions of greatest diameter lying substantially in the same cylinder, with opposite parts increasingly depressed to form a bore varying from a circular cross-section to one of an hour-glass form and with parts adjacent said depressions bent to provide an 25 excess of metal increasing in amount as said depressions increase in depth.
19. An expansion shield of sheet metal having more metal at one end than at the other, folded transversely into a tube with the outer portions of greatest diameter lying substantially in the same cylinder, with opposite parts increasingly depressed to form a bore varying from a circular cross-section to one of hour-glass form, with the central 30 part of the metal folded over one of said depressions and with the edges of the metal folded over the other of said depressions to provide an excess of metal over the tapered part of the bore, said excess of metal increasing in amount as said depressions increase in depth.
- 40 20. An expansion shield of sheet metal having more metal at one end than at the other, folded transversely into a tube with the outer portions of greatest diameter lying substantially in the same cylinder, with opposite parts increasingly depressed to form a bore varying from a circular cross-section to one of hour-glass form, with the central 45 part of the metal folded over one of said depressions and with the edges of the metal folded over the other of said depressions to provide an excess of metal over the tapered part of the bore, said excess of metal increasing in amount as said depressions increase in depth.
- 50 21. An expansion shield of sheet metal having more metal at one end than at the other, folded transversely into a tube with the outer portions of greatest diameter lying substantially in the same cylinder, with opposite parts increasingly depressed to form a bore varying from a circular cross-section to one of an hour-glass form and with parts adjacent said depressions bent to form longitudinal chambers flaring as the bore tapers.
- 55 22. An expansion shield of sheet metal having more metal at one end than at the other having transverse corrugations therein, folded transversely into a tube with the outer portions of greatest diameter lying substantially in the same cylinder, with opposite parts depressed to constrict the bore of the tube and with parts adjacent said depressions bent to provide an excess of metal at the part of the tube of constricted bore.
- 60 23. An expansion shield of sheet metal having more metal at one end than at the other, having transverse corrugations therein, folded transversely into a tube with the outer portions of greatest diameter lying substantially in the same cylinder, with opposite parts increasingly depressed to form a bore tapered in one of its transverse dimensions, and with parts adjacent said depressions bent to provide an excess of metal increasing in amount as said depressions increase in depth.
- 65 24. An expansion shield of sheet metal having more metal at one end than at the other having transverse corrugations intermediate the central part and the edges thereof, folded transversely into a tube with the outer portions of greatest diameter lying substantially in the same cylinder, with opposite parts increasingly depressed to form a bore tapered in one of its transverse dimensions with the central part of the metal folded over one of said depressions and with the edges of the metal folded over the other of said depressions to provide an excess of metal over the tapered part of the bore, said excess of metal increasing in amount as said depressions increase in depth.
- 70 25. An expansion shield of sheet metal having more metal at one end than at the other having transverse corrugations therein, folded transversely into a tube with the outer portions of greatest diameter lying substantially in the same cylinder, with opposite parts increasingly depressed to form a bore varying from a circular cross-section to one of hour-glass form with the central part of the metal folded over one of said depressions and with the edges of the metal folded over the other of said depressions to provide an excess of metal over 75

the tapered part of the bore, said excess of metal increasing in amount as said depressions increase in depth.

26. The process of making an expansion shield which consists in making a four-sided undivided sheet metal blank having one side of a length equal to the length of the shield, one end having a length approximately equal to the circumference of the completed shield and the opposite end having a greater length, and folding the blank transversely into a tube, with the outer portions thereof of greatest diameter lying substantially in the same cylinder, depressing opposite parts of the blank to constrict the bore of the tube and folding over parts adjacent said depressions to provide an excess of metal at the part of the tube of constricted bore.
27. The process of making an expansion shield which consists in making a four-sided undivided sheet metal blank having one side of a length equal to the length of the shield, one end having a length approximately equal to the circumference of the completed shield and the opposite end having a greater length, and folding the blank transversely into a tube, with the outer portions thereof of greatest diameter lying substantially in the same cylinder, increasingly depressing opposite parts of the blank to form a bore tapered in one of its transverse dimensions, folding the central part of the blank over one of said depressions and folding the edges of the blank over the other of said depressions.

28. The process of making an expansion shield which consists in making a four-sided undivided sheet metal blank having one side of a length equal to the length of the shield, one end having a length approximately equal to the circumference of the completed shield and the opposite end having a greater length, and folding the blank transversely into a tube, with the outer portions thereof of greatest diameter lying substantially in the same cylinder, increasingly depressing opposite parts of the blank to form a bore varying from a circular cross-section to one of hour-glass form, folding the central part of the blank over one of said depressions and folding the edges of the blank over the other of said depressions.

29. The process of making an expansion shield which consists in making a four-sided undivided sheet metal blank having one side of a length equal to the length of the shield, one end having a length approximately equal to the circumference of the completed shield and the opposite end having a greater length, cutting a longitudinal slot in the central part of the blank, and folding the blank transversely into a tube, with the outer portions thereof of greatest diameter lying substantially in the same

cylinder, increasingly varying from a circular cross-section to one of hour-glass form, folding the central part of the blank over one of said depressions and folding the edges of the blank over the other of said depressions.

30. The process of making an expansion shield which consists in making a four-sided undivided sheet metal blank having one side of a length equal to the length of the shield, one end having a length approximately equal to the circumference of the shield and the opposite end having a greater length, the sides of said blank flaring toward said ends, pinching the metal near the smaller end together to form outwardly projecting ribs, and folding the blank transversely into a tube.

31. The process of making an expansion shield which consists in making a four-sided undivided sheet metal blank having one side of a length equal to the length of the shield, one end having a length approximately equal to the circumference of the completed shield and the opposite end having a greater length transversely corrugating said blank, and folding the blank transversely into a tube, with the outer portions thereof of greatest diameter lying substantially in the same cylinder.

32. The process of making an expansion shield which consists in making a four-sided undivided sheet metal blank having one side of a length equal to the length of the shield, one end having a length approximately equal to the circumference of the completed shield and the opposite end having a greater length transversely corrugating said blank, and folding the blank transversely into a tube, with the outer portions thereof of greatest diameter lying substantially in the same cylinder, depressing opposite parts of the blank to constrict the bore of the tube and folding over parts adjacent said depressions to provide an excess of metal at the part of the tube of constricted bore.

33. The process of making an expansion shield which consists in making a four-sided undivided sheet metal blank having one side of a length equal to the length of the shield, one end having a length approximately equal to the circumference of the completed shield and the opposite end having a greater length, transversely corrugating the blank intermediate the central part and the edges thereof, and folding the blank transversely into a tube, with the outer portions of greatest diameter lying substantially in the same cylinder, increasingly depressing opposite parts of the blank to form a bore tapered in one of its transverse dimensions, folding the central part of the blank over one of said depressions and folding the edges of the blank over the other of said depressions.

34. The process of making an expansion

shield which consists in making a four-sided undivided sheet metal blank having one side of a length equal to the length of the shield, one end having a length approximately 5 equal to the circumference of the completed shield and the opposite end having a greater length, transversely corrugating the blank intermediate the central part and the edges thereof, and folding the blank transversely 10 into a tube, with the outer portions thereof of greatest diameter lying substantially in the same cylinder, increasingly depressing opposite parts of the blank to form a bore varying from a circular cross-section to one 15 of hour-glass form, folding the central part of the blank over one of said depressions and folding the edges of the blank over the other of said depressions.

35. The process of making an expansion 20 shield which consists in making a four-sided undivided sheet metal blank having one side of a length equal to the length of the shield, one end having a length approximately equal to the circumference of the completed 25 shield and the opposite end having a greater length, cutting a longitudinal slot in the central part of the blank, transversely cor-

rugating the blank intermediate the central part and the edges thereof, and folding the blank transversely into a tube, with the outer 30 portions thereof of greatest diameter lying substantially in the same cylinder, increasingly varying from a circular cross-section to one of hour-glass form, folding the central part of the blank over one of said 35 depressions and folding the edges of the blank over the other of said depressions.

36. The process of making an expansion shield which consists in making a four-sided undivided sheet metal blank having one side 40 of a length equal to the length of the shield, one end having a length approximately equal to the circumference of the shield and the opposite end having a greater length, the sides of said blank flaring toward said 45 ends, pinching the metal near the smaller end together to form outwardly projecting ribs, transversely corrugating the blank intermediate the central part and the edges thereof, and folding the blank transversely 50 into a tube.

In witness whereof, I hereunto set my hand this 31st day of March 1920.

JOSEPH KENNEDY.
